SNOWPLOW

Edward L. Wiedman, Tonawanda, N. Y.

Application December 8, 1944, Serial No. 567,199

17 Claims. (Cl. 37—42)

1

My invention relates to a snow plow, and more particularly to one designed for attachment to a passenger automobile, light truck, delivery automobile, or similar self-propelled vehicle.

One of the objects of my invention is to provide a snow plow of simple construction which can be conveniently folded into a small space, stored away so that it is easily accessible, and which is of a size that it can be placed within an automobile or the trunk compartment thereof, so that it can be conveyed from place to place as needed.

Another object of my invention is to provide a plow which can be easily converted into a scraper or which can be so arranged that it will direct the snow laterally in either direction, or in opposite directions.

A further object of my invention is to provide the plow with reach bars for attachment to an automobile, light truck or similar vehicle, and to provide an extension or adapter for use with either of the reach bars so that the plow share may be disposed to direct snow to one or the other side of the path in which the automobile or other vehicle to which the plow is attached is traveling.

The invention has for a further object, to provide an improved plow for private use which can be easily attached to and be as readily removed from an ordinary family automobile without subjecting operating parts of the latter to strain during the operation of plowing or scraping snow from any area, such as a driveway, the area leading to or surrounding a service station, or for the purpose of disposing of snow banks or drifts.

With the above-mentioned and other objects to appear hereinafter in mind, the invention consists in the construction, arrangement and combination of parts to be hereinafter described and more particularly pointed out in the subjoined claims.

In the drawings:

Fig. 1 is a perspective view of a portion of a passenger automobile having my improved plow attached thereto.

Fig. 2 is a front elevation of the plow as it appears when used as a scraper or pusher.

Fig. 3 is a top plan view of the plow, showing the same converted into a scraper or pusher and showing in dotted lines the position of parts as they appear when arranged to direct the snow to one side of the path along which the automobile is traveling.

Fig. 4 is a front elevation of the plow as it

2

appears when adjusting the plow-share thereof to direct the snow to opposite sides.

Fig. 5 is a top-plan view of the plow when the parts are positioned to direct the snow to opposite sides.

Fig. 6 is a broken longitudinal section on an enlarged scale, taken on the plane indicated by line 6—6, Fig. 3, with the reach-bar extension or adapter fastened to the rear or inner end of the reach-bar.

Fig. 7 is a horizontal section taken on line 7—7, Fig. 6.

Fig. 8 is an enlarged horizontal section taken on line 8—8, Fig. 6, looking up.

Fig. 9 is a side elevation through the connecting ends of the reach bar and its extension or adapter with adjoining parts directly associated therewith; part of the reach bar being shown in section to more particularly illustrate the manner of connecting the associated retainer-spring thereto.

Fig. 10 is an enlarged top-plan view of the inner hinged ends of the two sections of the plow share as these sections appear when aligned to convert the plow share into a scraper or pusher, or into a plow-share adapted to direct snow to one side.

Fig. 11 is a view similar to Fig. 10, showing the two sections of the plow-share disposed at an angle to each other so that snow will be directed to opposite sides.

Fig. 12 is a rear view of the plow-share, one section of which is broken to illustrate added length and the other broken away a distance beyond the hinge connection of the two sections.

Fig. 13 is a longitudinal section through one of the retainer-devices serving to hold the plow-share in vertical position.

Fig. 14 is an enlarged side elevation of one of the heads serving as a means of connection for the retainer-springs to the plow-share and the reach bars.

Fig. 15 is an enlarged side elevation of one end of one of the retainer-springs.

Fig. 16 is a vertical section taken on line 16—16, Fig. 12, looking in the direction of the arrow crossing said line.

Figs. 17 and 18 are detached perspective views of braces or gussets welded to the body portion of the plow share and to the stiffening elements extending horizontally along the lower portions of the two sections of the plow-share.

Fig. 19 is a rear view of a portion of one of the sections of the plow-share, showing the manner of folding the parti-circular racks and the reach bars and retainer-devices associated therewith.

55

Fig. 20 is a vertical section taken on line 20—20, Fig. 19, looking in the direction of the arrow crossing said line.

Figs. 21 and 22 are detached perspective views of the hinge members which are welded to the inner ends of the plow-share sections for connecting them together.

Fig. 23 is a top-plan view of the plow in folded condition.

Fig. 24 is a perspective sectional view of a portion of the bracing member for the lower end of each of the plow-share sections viewed from the front and top and showing a slot formed therein through which a brace or gusset is to be passed to be spot-welded to the rear face of the plow-share and which is to be welded in said slot.

Fig. 25 is a horizontal section taken on line 25—25, Fig. 19.

Having reference to the drawings in detail, the letter A designates an automobile, to the front end of which my improved plow is shown attached.

The reference numeral 26 designates my improved plow, which comprises a two-part plow-share 27, the two parts or sections 28, 29 of which are pivotally connected together at their inner ends, as at 30.

A reach device 31 is connected to each part or section. In some cases the reach device includes a reach-bar 32, while in other cases it includes the reach-bar 32 and a reach-bar extension or adapter 33. In either case, the reach device also includes a retaining-device 34 which extends from the reach-bar near its rear end to the plow-share near its upper end. The rear end of each reach-bar, or the rear end of the extension or adapter, when applied to the rear end of one of the reach-bars, is removably-attached to some part of the automobile and while this attachment may be made in any approved manner, I preferably utilize a hanger 35, which may depend from the bumper of the automobile, the bumper-arms thereof, or from any other portion of the automobile.

Since automobiles vary in construction, this hanger may be secured to any automobile part from which it is convenient to provide a depending arm or member which can serve as a hanger, or any portion of an automobile or a part secured thereto may be utilized for attaching the snow-plow thereto.

In Fig. 6 of the drawing, I have shown the hanger in the form of a flat bar fastened to one side of a bumper-arm 36 by means of a plate 37 applied to the opposite side of said arm by means of bolts 38 passed through said arm and plate and in contact with the upper and lower edges of said bar. In this figure, the bar is twisted between its ends so that its lower portion is at a right angle to its upper portion. When, however, a hanger of this type is used and applied to a bumper or any other transversely-disposed member of the automobile, the arm will be straight-lined from end to end.

Since it is the purpose of this invention to provide a plow-share which can be easily handled, the two sections 28 and 29 of the plow-share are constructed of comparatively light sheet metal stiffened to enable it to withstand all strains to which a plow-share is subjected and with this in mind, each section of the plow-share is formed of a single sheet of metal curved forwardly and upwardly along its upper end, as shown at 39, and having its marginal portion at said end re-

bent or curved rearwardly, as at 40, to stiffen the upper edge and to avoid sharp corners likely to catch against other objects. The lower portion of the sheet of metal is to serve as the lower end of a plow-share section, it being curved downwardly and forwardly, as at 41, and having its marginal portion bent downwardly, as at 42, and thence rearwardly, as at 43, leaving a rearwardly-opening groove 44, into which a portion of a brace member 45 is to be entered. This brace member is of Z-shape in cross-section so as to provide a vertical web 46, a rearwardly-extending flange 47 at the upper end of said web, and a forwardly-extending flange 48 at the lower end thereof, the marginal portion of which is entered in the rearwardly-opening groove 44, where it is spot-welded to the rearwardly bent marginal portion 43 of the plow-share. This brace member is welded to the body portion of the plow-share at the region where the rearwardly-extending flange 47 meets the web 46, as shown at 49, Fig. 6. Also disposed longitudinally along the rear of each of the sections of the plow-share is an angle piece 50, one flange of which lies against the rear of the section and is spot-welded thereto while its other flange lies against the upper surface of the rearwardly-extending flange 47 of the brace member 45 and is spot-welded thereto.

It is apparent, therefore, that the lower portions of the plow-share sections are measurably stiffened and bending of these lower portions is thus avoided when coming in contact with an obstruction. Applied to the rear surface of each plow-share section near its upper end, is an angle piece 51, one flange of which lies against said rear surface and is spot-welded to the section, the other flange extending rearwardly therefrom. A second angle piece 52 has one of its flanges 40 lying against the rearwardly-extending flange of said angle piece 51 and it is spot welded thereto while its other flange lies against the rear surface of the plow-share section and is spot-welded thereto. Thus the upper portion of each plow-share section is also stiffened and assurance provided against buckling of the same along said upper portion.

As clearly shown in Fig. 2, the inner end of one section overlaps the other and the inner edge of each section is so sheared or fashioned that along its medial portion it is straight-lined as at 53, the edge of the overlapping end being curved outwardly along its upper portion, as at 54, while its lower portion is also curved outwardly, as at 55, but preferably on a larger radius than at 54, for a purpose to appear hereinafter. The edge of the overlapped portion of the other section is also curved outwardly along its upper end, as at 56, and at its lower end, as at 57, the radius of the outwardly curved lower edge portion 57 being greater than the radius of the curved edge portion 56. The radii of the two curved edge portions 54 and 55 of the overlapping section 29 of the plow-share may be slightly greater than the radii of the correspondingly curved edge portions 56 and 57 of the overlapped section 29 of the plow-share, and in using the terms "overlap" and "overlapping," they apply only to the sections of the plow-share when they are positioned to serve as a scraper or pusher, or as a plow directing the snow to one side of the path in which the automobile is to travel, or, in other words, when the two sections trend in the same direction.

I preferably reinforce the outer ends of the

two sections 28 and 29 of the plow-share with angle irons 58, bent or fashioned to conform to the edge of each section at said ends. The angle irons 58 are curved at their upper ends, as at 59, to conform to the rounded corners of the plow-share and their lower ends may terminate slightly below the rearwardly-extending flange of the brace member 45. Each of these end angle irons has one of its flanges 60 lying in contact with and spot welded to the rear surface of the plow-share section and its other flange 61 extending rearwardly. The flange 60 terminates at its lower end at the upper edge of the angle piece 50 and extends upwardly to meet the inwardly-curved portion 59 of the rearwardly-extending flange 61. The outer ends of the flanges of the angle pieces 51 and 52, which lie against the rear surfaces of the plow-shares proper, are joggled so as to pass over the flanges 60 of the angle irons 58, and these joggled portions may be spot-welded to the flange 60. The outer ends of the rearwardly-extending flanges of the angle pieces 51 and 52 are bent at a right angle, as at 62, to lie against the inner faces of the flanges 61 of the angle bars 58 and they are spot-welded to said flanges.

The outer ends of the rearwardly-extending flanges of the angle pieces 50 and the rearwardly-extending flanges 47 of the brace members 45 are bent at an angle, as at 63, and these bent portions lie against the inner faces of the flanges 61 of the angle irons 58 and are spot welded thereto.

A hinge 64, which includes the pivot 30, connects the inner ends of the two sections of the plow-share so that they overlap in the manner described when the two sections of the plow-share trend in the same direction.

This hinge comprises two members, 65 and 66, each of which has an obliquely-disposed hinge leaf 67, along one edge of which spaced-apart pivot loops 68 are arranged, and when the two members are connected together, these loops are interfitting so that the openings therethrough are axially aligned to receive the pivot pin 30. Each of these hinge leaves has at its opposite edges a securing flange 10, the flange of one of said leaves being at an acute angle and the flange of the other being at an obtuse angle, as best shown in Figs. 10 and 11. The flange of one of these hinge members lies vertically against the rear face of one of the plow-share sections along its inner marginal portion, while the flange of the other hinge member lies against the rear face of the other plow-share section a distance from its inner edge and when the plow sections are disposed to trend in the same direction, the hinge leaves 67 lie one against the other.

The securing flanges of each hinge leaf is fashioned to conform to the cross-sectional shape of the plow-shares and it is spot-welded to the rear face of its associated plow-share section. The pivot loops of the hinge are situated a distance from the rear faces of said sections, due to the leaf portions thereof extending rearwardly from the securing flanges of the hinges.

With the view of guarding against the weakening of the welded securing flanges of this hinge, the hinge is also tied to stiffening members of the plow-share structure, under which term may be included the angle pieces 51 and 52 applied to the rear faces of the plow-share sections near their upper ends and the angle piece 50 and brace member 45 near and at the lower ends of the plow-share sections respectively. To ac-

complish this, I fasten a hinge bracket 71 to the upper side of the rearwardly-extending flange of the angle piece 52 of one of said plow-share sections at its inner end, and a co-acting hinge bracket 72 to the underside of the rearwardly-extending flange of the angle piece 51 of the other plow-share section at its inner end; each of these brackets having pivot holes therethrough, which are vertically aligned with the holes in the pivot-loops of the two hinge members 65 and 66. In a like manner, I fasten hinge brackets 73, 74 to the upper side of the rearwardly-extending flange of the angle piece 50 of one of said plow-share sections and to the underside of the rearwardly-extending flange 47 of the brace member of the other plow section 45, respectively. These brackets also have pivot holes therethrough, which are aligned with the holes formed in the pivot-loops of the hinge members 65 and 66, and the pivot pin 30 extends through the several hinge brackets.

When the two members or sections of the plow-share are disposed so as to trend in the same direction, the pivot of the hinge is arranged in a plane passing through overlapping portions of the plow-share, but when said members or sections are disposed at an angle to each other, as shown in Figs. 5 and 11, the pivot of said hinge is in a plane passing through the apex of the V formed by said plow-share sections. This is due to the formation of the inner edges of the plow-share sections and the disposition of said edges, respectively, when the plow-share sections trend in the same direction and when they are disposed at an angle to each other. Due to the forward curvature of the plow-share sections at their upper and lower ends, the curving of said edges at their upper and lower ends assure a close overlapping relationship when the plow-share sections are disposed to direct snow to opposite sides of the path in which the automobile is traveling, and only a slight laterally-opening space is formed between the inner overlapping marginal portions of the two plow-share sections, thus avoiding the formation of a direct opening at the apex of the V-shape then given the plow-share and the packing of snow behind the plow-share sections, which would tend to prevent proper operation of the plow.

To provide clearance between the two inner marginal portions of the plow-share sections, said marginal portions are curved inwardly on a radius having the pivot 30 as a center; or the overlapped marginal portion may be so curved and the overlapping marginal portion arranged in slightly greater spaced relation thereto to provide the necessary clearance for swinging the inner end of the overlapping section over the inner end of the overlapped section. It will, however, be apparent that by curving the inner marginal portion of both sections, using the axis of the pivot 30 as the center of the curves, a closer relation of the sections can be had when they are swung at an angle to each other.

The hinge structure described permits the two plow-shares to be folded into parallel relation with each other, back to back, as shown in Fig. 23, and when so arranged, the rearwardly-extending flanges of the angle pieces 51 and 52 of one section lie edge to edge with those of the other and similar disposition of the angle pieces 50 and the rearwardly-extending flanges of the brace members 45 also takes place so that a space or hollow is provided between the sheet metal parts of the two plow-share sections of a width more

than double that of the width of the rearwardly-extending flanges of the angle pieces 50 and 51 and 52. This space is utilized for a purpose to be hereinafter described.

To further render the plow-share rigid and resistant against strain applied thereagainst from various directions during the operation of the plow, I apply one or more braces or gussets 75 along the length thereof, directly above the rearwardly-extending flange of the angle piece 50. This brace or gusset comprises an elongated tapering member 76 and a securing flange 77 extending laterally from its inner or rear edge. The base of the elongated tapering portion is seated against the upper face of the rearwardly-extending flange of the angle piece 50 while the securing flange 77 extending therefrom lies against the rear face of the plow-share section. This flange is spot-welded to said section and the rear edge of said elongated tapering member or portion is cut away at its lower portion, as at 78, and lies against the upstanding flange of the angle piece 50. This brace or gusset is welded along its base to the rearwardly-extending flange of the angle piece 50 and along the cut-away portion 78 to the upstanding flange of said angle piece.

In line with and beneath each brace or gusset 75 is a second brace or gusset 79. This brace or gusset 79 comprises a brace member 80 and a securing flange 81 extending from its rear edge at a right angle thereto. This flange is curved to conform to the lower curved end of the body portion of the plow-share section to which it is applied and it is welded thereto. This brace or gusset 79 is secured to the body portion of the plow-share section before the brace member 45 is secured thereto, the latter having one or more slots 82 formed in its web 46 and extending forwardly partly through the forwardly-extending flange of the brace member so that when placing said brace member in position on the plow-share section, the outer and lower marginal portions of the brace or gusset 79 will extend into said slot, where it is welded so as to provide in effect, a unitary structure with the plow share and the brace member. While the braces or gussets 75 and 79 are shown in vertical alinement, they may be otherwise disposed and any number of these braces or gussets found necessary may be spaced along the length of each plow-share section.

The reach device 34 of each plow share section is connected to the section through the medium of an adjusting device 83, carried by the plow share section associated therewith for the purpose of adjusting the plow-share sections with respect to each other. The reach-bar for each section is connected to said adjusting device and each adjusting device includes a peripherally-notched semi-circular member 84 hinged to its associated plow-share section, the inner end of said member having a hinge leaf 85 connected therewith by means of a hinge pin 86. This hinge leaf is screwed or otherwise fastened to the upper face of the rearwardly-extending flange of the angle piece 50.

The semi-circular member has an opening 87 therein to provide a marginal arcuate bar 88 along the outer edge of which notches 89 are formed. The associated reach-bar extends rearwardly over the top of this semi-circular member, or semi-circular rack as it may be termed, and has its front end connected thereto near the hinge pin 86 by means of a pivot bolt 90 fastened in said member or rack and passed through a slot 91 formed in the reach-bar; thus establishing a com-

bined pivotal and slidable connection between the latter and said semi-circular member or rack.

Each reach-bar has a lock device 92 secured to its underside, which comprises a lock element 93 shaped at least in part to conform to the shape of the notches in the notched arcuate bar 88. This lock element is disposed at the outer side of the arcuate bar 88 and is fastened between the reach-bar and a retainer-bar 94 slidable against the underside of said arcuate bar. Between the reach-bar and said retainer-bar, a stop element 95 is arranged and this is disposed in spaced relation to the inner edge of said arcuate bar 88 when the lock element 93 is entered into any of the notches 89 in said arcuate bar. At such times the pivot bolt 90 is at the rear end of the slot 91 in the reach-bar and in order to prevent disengagement of the lock element 93 from the notched arcuate bar 88, a lock pin 96 is passed through registering openings formed in the reach-bar 32 and retainer-bar 94, said openings being then disposed in such relation to the inner edge of the arcuate bar 88 that the lock pin lies in contact with said edge and thus prevents longitudinal movement of the reach bar. When, therefore, the reach-bar is adjusted with reference to its associated plow-share section, or vice versa, the adjustment will be maintained under all operating conditions.

In order that the lock pin 96 may at all times be conveniently at hand, it may be fastened to one end of a short length of chain whose other end may be secured to some part of the reach-bar 32 or the semi-circular member or rack 84.

Each reach-bar is formed of angle iron, one flange of which is horizontally disposed and the other vertically. At the rear end of the horizontally-disposed flange, a lock-hook 98 is pivotally secured and this hook has extending forwardly from its pivot, an arm or handle 99 provided with a lateral extension 100 adapted to be passed through a slot 101 in the vertical flange of the reach-bar. This extension is provided with a lock notch 102 adapted to receive a pivoted lock latch 103, the pivot of which is passed therethrough and through said vertical flange. This lock latch has an arm 104 which is designed to normally assume a pendent position so that the lock latch tends to assume its locking position at all times; thus making it necessary to grasp the arm in order to swing the lock latch into a position that will disengage it from the extension 100 of the lock-hook 98 and thus permit the latter to be swung on its pivot for the purpose of disconnecting the reach-bar from the automobile, or the reach-bar extension or adapter 33, as the case may be, and as will be more particularly explained presently.

For the purpose of connecting the reach-bars to the hangers 35, each of the hangers is provided with an opening 105 through which the lock hook 98 of the associated reach-bar is passed and when this lock-hook is in locking position, the lateral extension 100 thereof projects through the slot 101 in the vertically-disposed flange of the reach-bar and is maintained in the locked position by the lock latch 103.

It is to be noted that each of the lock hooks 70 is gradually widened from its outer or free end inwardly toward its pivot and this has a tendency to bind the hook against the outer edge of the hanger and against at least one of the walls of the opening 105 therein; thereby preventing play and rattling noises.

When it is desired to utilize the plow-share for directing the snow to one side of the path in which the automobile is traveling, the plow-share sections are adjusted so that they trend in one and the same direction and at such times the plow-share is disposed obliquely with its trailing end at the side to which the snow is to be directed. When the plow-share is so disposed, an adapter is used in conjunction with the reach-bar at that side of the center of the plow-share which is more distant from the automobile. The front end of the reach-bar adapter is provided with an upwardly extending hook 106, which is passed through an opening in the reach-bar 32 directly forward of the arm or handle 99 on the lock hook 98 of the latter and the pivot of said lock hook, which extends downwardly below the under face of the reach-bar, as clearly shown at 101 in Fig. 6, enters an opening 108 in the reach-bar adapter.

The reach-bar adapter is also provided with an upwardly extending loop, or preferably a pair of registering loops 109, through which the lock hook 98 of the reach-bar 32 is passed and in this manner the front end of the reach-bar adapter 33 is connected to the rear end of the reach-bar 32 and thus a rigid extended or elongated reach-bar structure or device is provided. The rear-end of the reach-bar adapter is provided with locking mechanism similar to the locking mechanism at the rear end of the reach-bar proper, said locking mechanism including a lock hook and associated parts exactly like the lock hook and its associated parts at the rear end of the reach-bar, such parts being similarly numbered; the only exception being that the pivot of the lock hook 35 is fastened in place by means of a nut 110, see Fig. 6, whereas the pivot of the lock hook on the reach-bar 32 is welded in said reach bar and its downwardly-projecting portion is unthreaded so that it may freely enter the opening 108 in the reach-bar adapter.

Whether the reach-bars 32 are used alone or a reach-bar structure comprising the reach-bars 32 and the reach-bar adapter 33 are employed, the plow share is held in place thereby, it being the intention that the lower end of the plow-share ride over the snow-covered surface to be cleared as closely to the surface as possible so that only a comparatively thin layer of snow will remain on the surface after the snow-clearing operation is completed.

In order to maintain the plow-share in vertical position, each plow-share section is connected near its upper end with its associated reach-bar near its rear end by means of the yielding retaining device 34. Each of these retaining devices comprises a spiral spring 112, closely coiled together at opposite ends, as at 113, and having the convolutions of the spring somewhat separated between the closely-coiled ends. Each of the closely-coiled ends are threaded onto collars 114, each of which is provided with spiral grooves 115 adapted to have one of the closely-coiled ends of said spiral spring threaded thereon. In order that connection is maintained between these collars and the spring, the closely-coiled convolutions of the springs are welded to the collars.

Fastened to the collars 114 are eyes 116, the stems 117 of which are passed axially through the collars so that the threaded portions thereof extend beyond the inner faces of the collars and have nuts 118 threaded thereon in a manner to permit the stems of the eyes to rotate in said collars and thus provide a swivel connection between said eyes and said collars. Within the

spring, a long sleeve or hollow rod 119 is arranged, the ends of which surround the nuts 118. The ends of this sleeve bear against the inner faces of the collars 114 and in this manner the spring is prevented from buckling. The eye at one end of each spiral spring is fastened to a loop 120 secured to the rearwardly-extending flanges of the angle pieces 51 and 52 welded to the rear face of the plow-share section associated therewith. The eye at the opposite end of each of said spiral springs is secured in a loop 121 fastened to its associated reach-bar 32 near its rear end. Normally the springs 112 are under slight expansion, thus assuring maintenance of the collars 114 against the ends of the sleeves or hollow rods 119.

The yielding retainer devices also serve as means to prevent damage to or breakage of parts when the lower edge of the plow-share encounters an obstruction, such as a curb or other elevated object or portion of the surface over which the plow is to travel, in which case the curved lower end of the plow-share will be swung rearwardly, utilizing the hinge pin 86 as a fulcrum. This, therefore, causes the upper portion 20 of the plow-share to swing forwardly, whereupon the spiral springs 112 become expanded to a greater degree and permit the curved lower end 25 of the plow-share to swing into a position where it can freely ride over the obstruction, while the entire structure, including the reach-bars, and the reach-bar adapter if used, may move into a higher position, the reach-bar, and adapter if used, swinging on their respective hangers 35 as centers. It will be apparent, therefore, that the plow is self-adjustable so as to ride over obstructions and that when passing onto or beyond the obstruction, the retainer springs serve to return all parts to normal position.

In view of the fact that the lower end of the plow-share rides in close proximity to the snow-covered surface to be cleared, I have provided gliders 122 which tend, because of their small area, to work their way through the lowermost region of snow under the weight of the plow-share and thus tend to bring the lower end of the plow-share closer to the snow covered pavement or other surface, particularly when operating to clear fresh fallen or light snow from such surface. These gliders are stamped of sheet metal and are formed to provide a concavo-convex center 123, the convex face of which serves as a rider face, and a peripheral flange 124 designed to lie against and be spot-welded to the underside of the rearwardly-bent portion 43 at the lower end of the plow-share.

When the plow is not in use, the yielding retaining-devices may be detached from the plow-share sections and the reach-bars swung laterally on the notched rack 84 in either direction. The notched rack may then be swung upwardly against the rear of the section of the plow share to which it is pivotally connected. The two sections of the plow-share may then be swung together, back to back, and when so arranged, the edges of the angle pieces 50, 51 and 52 will lie in contact, creating a space between the two sections of the plow-share in which the yielding retaining-devices are confined and also the adjusting devices 33 and reach-bars. The plow-share sections may be maintained in folded position by fastening a hook 125 pivotally through the rearwardly-extending flanges of the angle pieces 51 and 52 on one section and engaging it 60 with a pin 126 secured to corresponding flanges.

11

of the other section, as shown in Fig. 23. It will be apparent, therefore that the plow share when folded, occupies comparatively little space and can be conveniently stored for future use and carted from place to place as required for use.

Having thus described my invention, what I claim is:

1. A snow plow, comprising a plow-share having two sections pivotally-connected together at their inner ends, and means extending rearwardly from said sections for attachment to an automobile, each of said plow-share sections being curved upwardly and forwardly at their upper ends and downwardly and forwardly at their lower ends, the inner ends of said plow-share sections being overlapped when trending in the same general direction, the inner edge of each of said sections being curved outwardly with the curvature at the lower ends of said edges on a greater radius than the curvatures at their upper ends so that when the sections are swung at an angle for directing snow to opposite sides of the path in which the plow is caused to travel the inner edges of said sections are in close juxtaposition throughout their lengths so as to prevent the passage of snow therebetween.

2. A snow plow, comprising a plow-share having two sections pivotally-connected together at their inner ends, and means at opposite sides of the pivot of said sections extending rearwardly from said sections for attachment to an automobile, each of said sections being curved downwardly and forwardly at its lower end and, the inner ends of said plow-share sections being overlapped when trending in the same general direction, the inner edge of each of said sections being curved outwardly so that when the sections are swung at an angle to each other for directing snow to opposite sides of the path in which the plow is caused to travel the inner edges of said sections are in close juxtaposition throughout their lengths so as to prevent the passage of snow therebetween.

3. A snow plow, comprising a plow-share having two sections pivotally connected together at their inner ends, a notched parti-circular element pivotally connected to each of said sections near their lower ends, a reach-bar arcuately adjustable over each notched parti-circular element and slidable in relation thereto and having a detent element adapted to enter any one of the notches therein to lock said reach-bars and notched parti-circular elements together, and a spring connecting the upper end of each plow-share section with its associated reach-bar to be expanded when the lower end of said plow-share encounters an obstruction and to retrieve itself after the plow-share passes over the obstruction.

4. A snow plow, comprising a plow-share having two sections pivotally connected together at their inner ends, a reach-device for each plow-share section having pivotal connection with the latter near its lower end, and a spring retainer-device connecting each section above its pivotal connection with its associated reach-bar a distance in rear of said pivotal connection, each spring-retainer-device comprising a spiral spring having stop elements at opposite ends, means of connection at said ends to its associated plow-share section and reach bar, respectively, and a sleeve within said spiral spring having opposite ends normally in contact with said stop elements to prevent contraction of said spring beyond a predetermined degree and buckling of the same and to permit expansion of said spring when the

12

lower end of said plow-share comes in contact with an obstruction to its forward movement.

5. A snow plow formed of a sheet of metal and having a rearwardly-extending flange near its lower end, a parti-circular peripherally-notched element pivotally connected to said flange, a reach-bar pivotally and slidably connected to said parti-circular element having a lock element free to travel along the peripheral edge of said parti-circular element when said reach-bar is at the end of its movement in one direction and being adapted to enter any selected notch of said parti-circular element when sliding said reach-bar to the end of its movement in an opposite direction, means to lock said reach-bar to said parti-circular element when said reach-bar is in its last-mentioned position so as to prevent swinging movement of the same, means at the rear end of said reach-bar for connection to an automobile part, and a yielding retainer-device positioned between said reach bar and the plow-share to maintain the two normally at a right angle to each other, said yielding means permitting swinging movement of said plow-share with respect to said reach bar when the lower edge thereof encounters an obstruction.

6. A snow plow, comprising a plow-share formed of sheet metal and having its lower portion curved downwardly and forwardly and its lower marginal portion rebent to form a rearwardly opening groove, a brace-member of Z-formation in cross section to provide a center web-portion, a rearwardly-extending flange at the upper end of said web-portion and a forwardly-extending flange at the lower end of said web-portion having its free marginal portion entered in said rearwardly-opening groove, said brace-member contacting said plow share at the conjunction of its center web-portion with its rearwardly-extending flange and being welded to the plow share thereat, an angle piece lying on and secured to said rearwardly-extending flange and having an upwardly-extending flange secured to the rear face of said plow-share, an adjusting-device comprising a parti-circular peripherally-notched element and a hinge leaf pivotally-connected to said parti-circular element and being secured to said angle piece, a reach-bar lying across said parti-circular element radially and being provided with a slot near its inner end, a bolt passed through said slot and parti-circular element near the connection thereof with said hinge leaf, locking means carried by said reach-bar selectively engageable with the notches of said parti-circular element when said bolt is at one end of said slot, said locking means being disengaged from said parti-circular element when said bolt is at the opposite end of said slot, and a spring retainer-device interposed between the plow-share and said reach-bar to maintain said plow-share normally in vertical position, said reach-bar having means at its rear end for connection with an automobile.

7. A plow-share formed of sheet metal and having its lower end curved downwardly and forwardly and rebent at its marginal portion to form a rearwardly-opening groove, a brace-member having a forwardly extended portion entered in said rearwardly-opening groove and extending along the rear of said plow-share, said brace-member being secured along its upper portion to said plow share and having a brace welded thereto and to the curved portion of said plow-share at least at one point along its length.

8. A plow-share formed of sheet metal and

13.

having its lower end curved downwardly and forwardly and rebent at its marginal portion to form a rearwardly-opening groove, a brace-member of Z-formation in cross section, having a central web-portion, a forwardly-extending flange entered in said rearwardly-opening groove and a rearwardly-extending flange at its upper end, said brace-member extending lengthwise of said plow-share and being welded at the junction of its web with its rearwardly-extending flange to 10 said plow-share, said web having at least one vertical slot in its web-portion, and a brace passed through said slot and having its front edge conforming to the curvature of said plow-share and being welded thereto, said brace having a portion extending rearwardly through said slot and being welded therein and to said rearwardly-extending flange.

9. A snow plow, comprising a plow-share, a reach-bar extending rearwardly from said plow-share, and a retainer-element connecting a high point of said plow-share with said reach-bar a distance from said plow-share, said reach-bar being of angular construction in cross section to form a horizontal flange and a vertical flange along one side of said horizontal flange, and a lock-hook pivotally connected to said horizontal flange at the rear end of said reach bar and having a handle extending forwardly from its pivot and a lock-arm extending laterally from said handle, the vertical flange of said reach bar having an opening through which said lock-arm is adapted to be passed and said lock arm having a notch near its outer end, a lock latch pivotally connected to the outer side of the vertical flange of said retainer-bar and adapted to lock into the notch of said lock-arm when the latter is thrust through said opening.

10. A snow plow, comprising a plow-share, a reach-bar extending rearwardly from said plow-share and having an opening vertically therethrough, a lock-hook pivotally connected to the rear end of said reach-bar and having its pivot extending below the lower face thereof, a reach-bar adapter having an L-shaped hook extending upwardly therefrom adapted to be passed through the vertical opening in said reach-bar and having an opening therein adapted to receive the downwardly-extending portion of the pivot of said lock-hook, said adapter having upwardly-extending co-acting means for engagement with the lock-hook of said reach-bar for connecting the latter and said reach-bar adapter rigidly together.

11. A snow plow, comprising a plow-share having two plow-share sections pivotally connected together at their inner ends so that they may trend in the same direction or be disposed at an angle to each other, each plow-share section having a rearwardly-projecting element disposed horizontally and provided with a parti-circular series of notches, reach bars for said plow-share sections adapted for connection at their rear ends with fixed parts of an automobile and pivotally-connected at their front ends to 55 said rearwardly-projecting elements, the pivots of said reach bars being the centers of said parti-circular series of notches, and means on said reach bars to lock the latter in any selected notches of said rearwardly projecting elements in accordance with the disposition of said plow-share sections.

12. A snow plow, comprising a plow share having two plow-share sections pivotally connected together at their inner ends so that they

14.

may trend in the same direction or be disposed at an angle to each other, a reach bar pivotally connected to each of said sections between its ends to permit said bar to be swung horizontally in an arc of a circle and co-acting means carried by said plow-share sections and said reach-bars for locking the latter in any desired angular position.

13. A snow plow, comprising a plow-share having two plow-share sections pivotally connected together at their inner ends and being foldable back to back with a space between at least portions thereof when folded, means of connection between each plow-share section and a fixed point of an automobile including adjusting means to permit of adjusting said plow-share sections relatively, and retaining means connecting the upper portions of said plow-share sections with said connecting means a distance in rear of said sections, said connecting means including its adjusting means and said retaining means being foldable on their respective plow-share sections to position them within the space between said sections when the latter are folded back to back.

14. A snow plow, comprising a plow-share having two sections pivotally connected together at their inner ends, a reach-device for each section extending rearwardly therefrom, each reach-device including a notched parti-circular element hingedly connected to its associated plow-share section, a reach-bar pivotally secured at its forward end to said parti-circular element at the center thereof and having its rear end adapted for connection with a part of an automobile, means carried by said reach-bar to lock into any selected notch of said parti-circular element, and a yieldable retainer-device for each plow-share section connected thereto near its upper end and with the reach-device associated therewith a distance in rear of its associated notched parti-circular element, said yieldable retainer-device enabling the lower end of the plow-share to ride over an obstruction and immediately retrieve its normal position after passing such obstruction.

15. A snow plow, comprising a plow-share having two sections pivotally connected together at their inner ends, a reach-device for each section extending rearwardly therefrom and serving to secure the plow-share to an automobile and to permit the plow-share sections thereof to be adjusted relatively from a straight line position to an angular position, or reversely, and to permit said plow-share sections to be folded back to back when storing the plow-share, each reach-device including a notched parti-circular element pivotally connected to its associated plow-share section and a reach-bar pivotally secured at its forward end and having its pivot co-axial with the center of said notched parti-circular element and its rear end adapted for connection with a part of an automobile, said reach-bar having means to engage any selected notch of said parti-circular element to adjust the plow-share sections as desired, and suitable retainer-means for retaining said plow-share sections in desired vertical position.

16. A snow plow, comprising a plow-share having two sections pivotally connected together at their inner ends, a notched parti-circular element connected to each of said sections and normally extending rearwardly therefrom, a reach-bar arcuately adjustable along each 70 notched parti-circular element, means to lock

15

said reach-bars and notched parti-circular elements together, and means connecting the upper end of each plow-share section with its associated reach-bar.

17. A snow plow, comprising a plow-share having two sections pivotally connected together at their inner ends and normally in substantially vertical position, a reach-bar for each of said snow plow sections extending rearwardly therefrom and having means of connection between its forward end and its associated plow-share section to enable the latter to swing on the pivot connecting said plow-share sections together for adjusting the latter relatively, to provide a horizontal pivot on which the plow-share section may swing from its normal vertical position when striking an obstruction in the path of travel and to maintain said plow-share sections in relatively adjusted positions, yielding means to retain said plow-share sections in normal vertical position, and reach-bar adapters to be used selectively with said reach-bars, said reach-bars having

5

16

means for connection at their rear ends with the front ends of said adapters and the latter having means at their rear ends adapted for connection with an automobile part.

EDWARD L. WIEDMAN.
